(57) CLAIM

The ornamental design for a Christmas tree, as shown and described.

DESCRIPTION

FIG. 1 is a front perspective view of a Christmas tree showing my new design, with the bottles attached shown in broken lines and form no part of the claimed design;

FIG. 2 is a top view thereof;

FIG. 3 is a bottom view thereof;

FIG. 4 is a front view thereof, where the back view is identical to the front view; and,

FIG. 5 is a left side view thereof, where the right side view is identical to the left side view.

1 Claim, 4 Drawing Sheets

FIG. 1

FIG. 2

FIG. 3

FIG. 4

FIG. 5
